UNITED STATES PATENT OFFICE.

DWIGHT D. KING, OF SUNBEAM, COLORADO.

DESIGN FOR A LAMP.

51,143.

Specification for Design. Patented Aug. 14, 1917.

Application filed June 26, 1917. Serial No. 177,143. Term of patent 14 years.

To all whom it may concern:

Be it known that I, DWIGHT D. KING, a citizen of the United States, residing at Sunbeam, in the county of Moffat and State of Colorado, have invented a new, original, and ornamental Design for Lamps, of which the following is a specification, reference being had to the accompanying drawing, forming a part thereof.

Fig. 2 is a side view, and

Fig. 3 is a front view.

I claim:

The ornamental design for a lamp, as shown.

DWIGHT D. KING.

Witnesses:

DEAN E. SHAFFER,
FRANK N. GRAHAM.
